UNITED STATES PATENT OFFICE.

JAMES PENNINGTON, OF WARINGSTOWN, NORTHERN IRELAND.

DESIGN FOR TABLECLOTH OR SIMILAR ARTICLE.

Application filed January 27, 1928, Serial No. 25,048, and in Great Britain December 14, 1927.
Term of patent 14 years.

To all whom it may concern:

Be it known that I, JAMES PENNINGTON, a subject of the United Kingdom of Great Britain, and a resident of Waringstown, county Down, Northern Ireland, whose post-office address is Waringstown, county Down, Northern Ireland, have invented a new, original, and ornamental Design for Tablecloth or Similar Article, of which the following is a specification, reference being had to the accompanying drawing, forming part thereof.

The figure is a plan view of a tablecloth.

I claim:—

The ornamental design for tablecloth or similar article, as shown.

In testimony whereof I affix my signature.
JAMES PENNINGTON.
